UNITED STATES PATENT OFFICE.

JOHN E. GREENAWALT, OF DENVER, COLORADO.

OIL-BURNER.

1,084,939.

Specification of Letters Patent. Patented Jan. 20, 1914.

Application filed March 24, 1913. Serial No. 756,519.

To all whom it may concern:

Be it known that I, JOHN E. GREENAWALT, citizen of the United States, residing at Denver, in the county of Denver and State 5 of Colorado, have invented certain new and useful Improvements in Oil-Burners, of which the following is a full, clear, and exact description, reference being had to the accompanying drawings, forming a part 10 hereof.

My invention has relation to improvements in oil (and vapor) burners, and it consists in the novel details of construction more fully set forth in the specification and 15 pointed out in the claims.

In the drawings, Figure 1 is a side elevation of an ore-sintering pan surmounted by an ignition hood, showing my invention applied thereto, parts being broken away;

20 Fig. 2 is a vertical cross-section on the line 2—2 of Fig. 1; Fig. 3 is a part elevation and part vertical middle section of the burner on a larger scale; Fig. 4 is a horizontal section on the line 4—4 of Fig. 3; Fig. 5 is a 25 horizontal section on the line 5—5 of Fig. 3, parts being broken away; Fig. 6 is a detached plan view of the slotted disk through which the burner fluid is sprayed; Fig. 7 is an edge view of Fig. 6; and Fig. 8 is a 30 plan of a disk having a series of slots of unequal widths.

The present invention is directed to burners specially adapted for use in connection with the roasting and sintering of 35 ores *en masse* where it becomes important to simultaneously ignite the entire surface of the charge in order to insure an even and uniform propagation therethrough of the zone of combustion. This simultaneous

40 ignition of an extended surface of the charge depends for its success upon the intensity and direction of projection of the igniting fuel over such surface, especially in processes where the charge is subjected to the

45 action of a downdraft current of air to supply the oxygen to the combustible components of the charge. Instances of such downdraft for purposes of roasting and oxidizing and sintering ores are to be found in

50 my U. S. Patent 839,065, dated December 18, 1906, and in my pending application for sintering apparatus, filed June 24, 1912, Serial Number 705,495. Where, as in the latter example a charge is sintered *en masse*, provision must be made to effect a simultaneous 55 ignition of the entire surface of said

charge; and to accomplish this effectively, burners must be employed which will not only project the igniting fuel across the charge in paths substantially parallel to its 60 surface, but with sufficient intensity to prevent material deflection of the projected streams by the transverse currents of air traversing the body of the charge from top downward, such traverse as well understood, 65 being due to the action of the exhauster producing the downdraft. If the projected streams of igniting fuel were deflected by the downdraft to any material extent, a considerable proportion thereof would be 70 sucked or drawn into the body of the charge before the fuel could be ignited above the charge, the portion thus prematurely drafted into the charge being lost and rendered unavailable for the purpose for which it was 75 intended.

It is therefore one of the objects of my present invention to construct a burner which will subdivide a given charge of liquid igniting-fuel into a plurality of streams 80 or jets, and project these streams preferably under a sufficient pneumatic head, over a wide area, said area being disposed in a plane directly over, and parallel to, the surface of the charge of ore (or other material) 85 to be treated. Air under pressure is preferably employed as the impelling agent by which the projection of the fuel is effected, although any equivalent gas may be substituted for air.

90 A further object is to provide a burner which is capable of a wide range of service, the invention not being limited in its application to the specific use of an igniter for ore charges.

95 A further object is to construct a burner which is simple, reliable, positive in action, durable, containing a minimum number of parts; one adapted to operate on gaseous and solid, as well as liquid fuels, producing 100 a flame of uniform intensity covering an extensive area; and one possessing further and other advantages fully apparent from a detailed description of the invention which is as follows:—

105 Referring to the drawings, and for the present to Figs. 1 to 7 inclusive, 1 represents a pan or treatment receptacle which in practice may be of any convenient size, the dimensions of that here shown being about 110 twelve feet in length, seven feet wide, and two feet deep, the same being provided with

grates G or equivalent perforated support for the charge *m*, the thickness of the charge being about twelve inches, and the upper surface thereof disposed substantially flush 5 with the edges of the pan. The grates are raised above the bottom of the pan so as to leave a vacuum chamber 4 between the grates and said bottom, the pan being provided with hollow trunnions 5 (about which it is 10 rotatable) communicating respectively with said chamber 4 and with a suitable exhauster (not shown). Adapted to be deposited on the pan directly over the charge is a hood H the roof of which is sufficiently raised above 15 the surface of the charge to form a combustion or igniting chamber 6 above the charge, the parts thus far described being in all essential particulars the same as in my pending application aforesaid, and being referred to herein in order to show their relation to the burner to which my invention 20 is specifically directed. In the present application of my invention I employ two burners B, B, mounted on the roof of the 25 hood and discharging into the chamber 6, there being one burner on each side of the transverse axis of the hood, and removed equal distances from said axis, each burner thus covering or igniting an area six by 30 seven feet, of the total area of twelve by seven feet of the ore charge. Mounted above the hood and supported thereby in any mechanical manner is an oil tank T, from the bottom of which leads a discharge T 7 communicating with an oil line 8 disposed parallel to the length of the tank and extending in opposite directions from said T 7, each branch of said line being provided with a suitable control valve V beyond which is located 35 a standard Schutte-Koerting strainer 9, the branches of the oil line discharging into the burner, through the top thereof. Tapping the oil tank at the top and communicating with the air space above the oil 40 in the tank is a compressed-air supply pipe 11 provided with an air-valve 12, said pipe connecting to a suitable flexible hose 13 which leads to any suitable source of compressed air supply (not shown). The compressed 45 air or other gas in the tank T above the surface of the oil discharges through a reducing valve, pop valve, or equivalent pressure-regulator 15, into an air-line 16, the said line running in opposite directions from the valve 15, each branch discharging 50 tangentially into its respective burner, the air-branches being likewise provided with a standard make of strainer 9'. The novelty of the foregoing features resides of course 55 in the relation of the several parts to one another, and not in the specific construction of any one element.

Directing our attention to the construction of the burner *per se*, and to its specific 60 disposition within the igniting chamber 6,

the said burner is composed of two sections *a*, *b*, the former being hollow or tubular and substantially cylindrical in form, the sections being united to one another by means of bolts 17 passed through the section *b* and through the basal enlargement *a'* of the section *a*. Between the sections there is interposed a sheet metal plate or disk 18 or equivalent spacing member, the said disk resting on the inner face of the section *b* and being provided with a series of radial slots *s* open at their outer ends, the inner closed ends thereof terminating within the chamber C of the burner as shown, the disk having a central circular imperforate section *h* from the periphery of which the slots radiate. The slots thus form radial channels with the opposing faces of the sections *a*, *b*, for the escape of the oil from the chamber of the burner into the atmosphere. The 75 portion *h* of the disk serves as a support for the central spreader or cone 19 which is secured to the disk and to the section *b* of the burner by a screw-bolt 20 or equivalent mechanical manner. The cone serves not 80 only to hold the disk 18 firmly against the bottom section *b*, but it likewise serves to distribute and direct the oil into, the several channels aforesaid. The base of the cone 19 comes inside the closed terminals of the slots 85 or channels *s*, whereby free communication is afforded through the channels between the atmosphere and the chamber C (termed for convenience as the mixing-chamber). The disk 18 is provided with holes O for the accommodation of the bolts 17.

As seen from the drawings, the plane of separation between the burner sections *a*, *b*, is at right angles or transverse to, the axis of the mixing chamber, so that the paths 105 of discharge of the oil and gases from the burner are in the corresponding plane, any oil not fully atomized being caught in the gutter 21 formed around the periphery of the burner-section *b*. The upper end of the 110 burner-section *a* is provided with a hollow screw-plug 22 to which are respectively secured the discharge end of the oil-line branch 8 (the connection being made by an elbow 23 passed over the end of said branch 115 and over a pipe 23' inserted into the plug), and a standard spray-nozzle 24, the latter being preferably of the Schutte-Koerting variety well known in the art. The axis of 120 the spray-nozzle is coincident with the axis of the burner as shown, whereby the spray of oil is symmetrical about said axis. The air line 16 communicates with the mixing chamber at the top thereof, the air being introduced preferably at a tangent to the inner wall of the chamber whereby a whirling movement is imparted to the air within the chamber. The connection is made at the opening 25 in the boss 26 of the wall of 125 the section *a*. The spray-nozzle 24 requires 130

at least fifteen pounds pressure to spray the oil into the free atmosphere at ordinary temperatures and some heavier oils require even more. The oil herein however, is sprayed into the chamber C which itself is under a pressure approximating forty pounds, so that the pressure required to force the oil into the chamber, other things being equal, will be fifteen plus forty pounds or approximately fifty-five pounds. The slots s though shown in the figures aforesaid as being of uniform size, may have one or more of them as s' enlarged over the others as shown in the modification in Fig. 8, such enlargement allowing a greater volume of air to pass through, and hence projecting further the flame at such points.

In the specific application of the burner as here shown, its success depends on the accuracy and perfection with which the oil is subdivided and delivered to the radial slots or channels s. In other words, it is important that each slot or channel shall receive exactly the same amount of oil. This accurate subdivision follows to a considerable degree from the use of the spreader or cone 19, which as heretofore stated directs the distribution of the oil into its proper channels. The said subdivision likewise depends for its full realization on the use of the spray nozzle within the mixing chamber C whereby the oil is fully atomized or subdivided before it is delivered to the channels s (of which there should always be a plurality) through which the oil is delivered in radial sprays or jets by the blast of air or other gas entering said chamber under pressure from the oil tank. The degree of pressure availed of to project the oil through and out of the channels depends on the area it is desired to cover with the flame; the greater the area the greater the pressure necessary to project the oil or resulting flame. The air being under pressure flows through slots or channels in proportion to the cross-sectional area of the slot, the volumes of air passing through the slots being equal if the cross-sectional areas of the slots are equal, the projected streams being substantially of equal length. It will be seen that the streams of sprayed and atomized oil projected from the channels s being disposed in substantially the same plane, will collectively form an inflammable sheet of atomized fuel which when ignited will form a sheet or blanket of flame, said blanket (if sufficient driving pressure be behind it) being coextensive with the surface of the charge and serving to simultaneously ignite the entire surface of said charge. To render this possible, it is of course obvious that the intensity of projection of the streams must be such as not to suffer any material deflection from their substantial parallelism with the surface of the charge (to be ignited) by

the transverse air currents traversing the charge from top downward, in response to the action of the exhauster, otherwise some of the inflammable material or oil-spray would be drawn prematurely into the body of the charge and there lost, not having a chance to form into flame before suffering the deflection referred to.

The operation of the burner employed in the connection here described may be stated as follows:—Air under sixty (60) pounds pressure or more is delivered to the oil tank T into the space above the oil whereby the oil is delivered at said pressure to the spray-nozzle 24, the said nozzle subdividing and spraying the oil into the mixing chamber. This subdivision of the oil permits each channel or slot s to receive its proper proportion of oil so that the resulting flame is one of uniform intensity and spreads over an extended area (each burner in fact discharging a flame coextensive with one-half the surface of the charge in the pan 1). The air as it passes from the tank flows through the reducing valve 15 which reduces the pressure say about eighteen pounds, thus allowing the air blast which enters (tangentially) the chamber of the burner to flow into said chamber at about a pressure of forty-two pounds (more or less), the consequent intimate mixture of sprayed oil and air passing into the channels s (at a pressure which will depend on the relation between the combined areas of the channels s, and the area of the opening 25), the oil being again atomized and sprayed as it discharges from the channels. The sprays being delivered substantially at right angles to the axis of the burner, and said axis being perpendicular to the (horizontal) surface of the charge m, it follows that the series of radial sprays thus projected from each burner will collectively form a sheet of inflammable particles which when ignited will result in a sheet of flame or in a burning blanket which in turn effectively and almost instantaneously (and before the inflammable particles can be prematurely deflected into the charge by the exhauster) ignites simultaneously the entire surface of the section of the charge which is beneath said blanket, each burner thus igniting one-half of the surface of the ore charge, and both burners igniting the entire surface of such charge. Inasmuch as both burners work simultaneously, it follows that both sections of the surface of the charge will be ignited at one and the same time, so that the zone of combustion of the combustible components of the charge will propagate itself evenly and uniformly through the charge from top downward in the general direction of the transverse air currents drafted through the charge by the action of the exhauster. The burner here shown operates

on a minimum amount of liquid compared with the size and intensity of the sheet-flame produced, and may be used in many arts not necessarily akin to roasting or sintering ores. For example, it may be used as a distributor in scrubbing and acid towers where a small volume of liquid is uniformly distributed in sheet form over large areas. Other uses will suggest themselves to those skilled in the respective arts where such a device is available. It becomes a "burner" of course only where the sheet of spray is ignited and produces a flame; in other cases it serves as a mere distributor.

The pressure "differential" or excess of eighteen pounds pressure here alluded to under which the oil is driven into the chamber of the burner member against the pressure of air or gas maintained within said chamber for expelling the liquid, may of course vary. This differential will depend in a measure on the kind of spray-nozzle used, on the radius of projection of the streams desired through the slots (or equivalent vents), the cross-sectional areas of the slots, and on a variety of circumstances. The proper differential however, can always be determined by the operator according to the work to be performed. The driving pressure of the liquid should of course be in excess of the gas pressure maintained in the mixing chamber so as to insure the projection of the liquid into the chamber. It may be added that in lieu of liquid fuel any fluent material gaseous or solid may be substituted.

In the practice of my invention as described, the oil sprayed from the burners may be ignited either as the hood is being deposited over the pan, or it may be ignited after the pan is deposited by a torch inserted through a torch-hole (not shown) placed where convenient, according to the wish of the operator.

In the claims the term "member" is to be understood as meaning the entire burner member without regard to the sections which compose it, the sectional character of the burner being an advantage in that it permits the use of any style spray disk 18, it being possible to change a disk at any time when occasion arises to change the number, or vary the size of the slots or channels s . In this connection it may be stated that by providing a spray-disk (such as 18) with slots s , s' , of various widths (or unequal dimensions) we can vary the distance of projection through the different slots, and hence vary (to suit our purpose) the areal configuration or shape of the resulting sheet of inflammable material formed by the sum total of all the sprays discharged from the disk. For example by providing the disk with radial slots of equal dimensions there results substantially a circular sheet of sprayed material: by varying the dimensions

of some of the slots we could secure a square or polygonal sheet, so that any areal configuration of sheet is possible.

Features shown but not alluded to are old in the art, or are already embodied in my pending application aforesaid, and a description of the same is here unnecessary, especially as they form no part of the present invention.

Having described my invention, what I claim is:—

1. A burner comprising a tubular member provided with an axial intake opening at one end, the opposite end being closed, a series of channels disposed at the closed end and communicating respectively with the chamber and the burner, and with the atmosphere through the walls of the burner, and operating to discharge the inflammable material in sheet form in a plane disposed at an angle to the axis of the tubular member; means for supplying gas under pressure to said chamber, and means for projecting sprayed fluent material into the chamber toward said channels through the intake opening aforesaid.

2. A burner comprising a tubular member provided with an axial intake opening at one end, the opposite end being closed, a series of radially disposed channels at the closed end communicating respectively with the chamber of the burner, and with the atmosphere through the walls of the burner, and discharging in paths substantially at right angles to the axis of the tubular member, means for supplying gas under pressure to said chamber, and means for projecting in a finely divided state fluent material through the intake opening aforesaid toward said channels.

3. A sectional burner comprising a tubular section having an axial intake opening at one end, a second section closing the opposite end of the first section, means forming a series of channels between the sections discharging into the atmosphere, the inner ends of the channels communicating with the chamber of the burner, means for supplying gas under pressure to said chamber, and means for projecting sprayed fluent material into the chamber toward said channels through the intake of the tubular section.

4. In a sectional burner, a tubular section having an axial intake opening for fuel at one end thereof, a second section closing the opposite end of the tubular section, a disk having a series of radial slots open at their outer ends and terminating a suitable distance from the center of the disk, said disk being interposed between the sections, and the slots thereof forming channels establishing intercommunication between the chamber of the burner and the atmosphere, for the purpose set forth.

5. In a sectional burner, a chambered sec-

- tion having an axial intake opening for fuel at one end thereof, a second section closing the opposite end of the chamber, a disk having a series of slots communicating at their 5 inner ends with the interior of the burner chamber and discharging into the atmosphere, said disk being interposed between the sections, and means in the chamber for evenly distributing the fuel to the several 10 slots.
6. A burner comprising a tubular substantially cylindrical section having an axially disposed intake at one end, a second section closing the opposite end of the first section 15 and separable therefrom along a plane disposed at right angles to the axis of the tubular section, a radially slotted disk interposed between the sections the slots thereof forming channels establishing communication be- 20 tween the inner chamber of the burner and the outer atmosphere, a substantially conical spreader at the center of the disk, means for securing the disk and spreader to the second section, a spray nozzle in the burner chamber 25 leading from the intake opening and adapted to project a spray of liquid fuel into the chamber, means for delivering gas under pressure through the wall of the tubular section into the chamber, the parts operating substantially as, and for the purpose set forth.
7. In a burner, a chamber provided with a terminal intake opening and peripheral discharge means, a gutter disposed adjacent the
- outer boundaries of the discharge means and 35 out of range of projection from said discharge means, for the purpose set forth.
8. A tubular burner having an axial intake at one end, and peripheral discharge means adjacent the opposite end, and means for 40 conducting gas under pressure into the burner chamber at a point adjacent to the intake end and in paths substantially tangential to the inner surface of the walls of the burner, for the purpose set forth. 45
9. A burner comprising a tubular member provided with an axial intake opening at one end, the opposite end being closed, a series of radial channels disposed at the closed end and communicating respectively 50 with the chamber of the burner, and with the atmosphere through the walls of the burner, means for supplying gas under pressure to said chamber, means for projecting inflammable material into the chamber toward said channels through the intake opening aforesaid, the channels operating to distribute the streams of inflammable material discharged therethrough in a plane disposed at an angle to the axis of the tubular mem- 55 ber. 60

In testimony whereof I affix my signature, in presence of two witnesses.
